DESIGN FOR AN UMBRELLA OR SIMILAR ARTICLE

Edward E. Seldis, New York, N. Y.

Application March 30, 1944, Serial No. 113,073

Term of patent 7 years

(Cl. D88—3)

To all whom it may concern:

Be it known that I, Edward E. Seldis, formerly a citizen of Germany, who has declared his intentions of becoming a citizen of the United States, residing in New York city, in the county of New York and State of New York, have invented a new, original, and ornamental Design for an Umbrella or Similar Article, of which the following is a specification, reference being had to the accompanying drawing, forming part thereof.

Fig. 1 is a front view of an umbrella or similar article showing my new design, and

Fig. 2 is a top plan view thereof.

The characteristic features of the design reside in the portions shown on the drawing in full lines.

I claim:

The ornamental design for an umbrella or similar article, substantially as shown and described.

EDWARD E. SELDIS.
